UNITED STATES PATENT OFFICE.

LEOPOLD FRANK, OF LONDON, ENGLAND.

GLOVE.

SPECIFICATION forming part of Letters Patent No. 468,149, dated February 2, 1892.

Application filed December 30, 1891. Serial No. 416,513. (No model.) Patented in England June 10, 1891, No. 9,866.

To all whom it may concern:

Be it known that I, LEOPOLD FRANK, of the city of London, England, have invented certain new and useful Improvements relating to 5 Gloves, (for which I have obtained Letters Patent of Great Britain No. 9,866, dated June 10, 1891,) of which the following is a specification.

This invention relates to the manufacture of ladies' and gentlemen's gloves of a new and 10 useful character.

My improved gloves are provided with 15 means for enabling wearers to reflect their personal appearance when desired, while the gloves serve their ordinary purposes without any inconvenience to the wearer.

In carrying out this invention I adapt to the palm of the left hand a mirror made either of 20 burnished metal or of flat, concave, convex, or concavo-convex silvered glass. The mirror is mounted in a setting or frame secured 25 to the inside of a reversible flap, which is so attached to the glove and provided with a fastening that the gloved hand may be opened without presenting a noticeably peculiar appearance 30 until it is desired to use the mirror, when by the disengagement of the fastening the flap may be turned to present the mirror to view. This arrangement of a mirror on a glove constitutes a new and improved article 35 of manufacture which supplies a trade want.

In the accompanying drawings, Figure 1 shows the palm of a glove with my improvement adapted thereto. Fig. 2 is an enlarged section taken on the line $x-x$, Fig. 1.

35 a is the mirror, which is mounted on a flap b, sewed to the palm of the glove at e e in a convenient position. The tab end of this flap carries a snap-fastening c, which fits a metal stud d, secured to the glove, and completes the 40 mirror attachment to the glove. In some cases a button-hole fastening may be employed.

It is obvious that when preferred the position of the mirror may be varied by fixing it and its fittings—say in the case of a long 45 glove—in the arm thereof.

The mode of securing the mirror in the flap will now be described.

The flap is made of two thicknesses of material, which I will refer to as *b* and *b'*, the piece *b* forming the outside and *b'* the inside 50 of the flap. The piece *b'* having been cut of the desired shape and size, the mirror *a* is placed in the center thereof with the reflecting side uppermost. The material is then gathered up round the mirror and is passed 55 through a ring *f*, preferably of thin metal and of slightly less diameter than the mirror. The material is next spread out flat over the ring and is secured by its edges to the piece *b*, and the one edge of the flap thus formed is secured 60 to the glove by sewing, as shown at *e e*. In this manner the mirror, secured in a kind of light frame, is so attached to the glove that under ordinary circumstances it cannot be detached therefrom.

When the flap is turned up to the position shown in dotted outline in Fig. 1 and the two members of the fastening *c d* are engaged, the gloved hand may be opened without presenting a noticeable peculiar appearance; but 70 when the wearer desires to use the mirror the disengagement of the fastening *c d* allows the flap to drop to the position shown in full outline in Figs. 1 and 2, in which the mirror is in a convenient position for use.

75 What I claim as my invention, and desire to secure by Letters Patent, is—

A glove having attached to its outer surface a reversible flap and having attached to the inner face of said flap a setting or frame 80 containing a mirror, the said glove and flap having, respectively, provided upon them the two members of a fastening for securing the flap, substantially as herein set forth.

LEOPOLD FRANK.
